FRANK W. CHRISTY AND JAMES A. TORREY, OF BEVERLY, MASSACHUSETTS

PRESSING DEVICE FOR SOLE-LAYING MACHINES

Application filed December 31, 1928. Serial No. 329,565.

This invention relates to improvements in pressing devices for sole laying machines and has for its object to provide a simple and efficient device for securing a sole to a shoe upper by pressure which will be distributed equally over the entire surface of the sole and which will press with equal effectiveness different sizes and styles of shoes.

The invention consists in an improved pressing device for sole pressing or laying machines as set forth in the following specification and particularly as pointed out in the claims thereof.

Referring to the drawings:

15 Figure 1 represents a plan view of a pressing device embodying our invention.

Fig. 2 is a side elevation of the device.

Fig. 3 is a central vertical section through the pressing device taken on the line 3—3 of Fig. 1, the device being illustrated in the position it assumes when a sole is being pressed against a shoe upper.

Fig. 4 is a transverse section taken on the line 4—4 of Fig. 1.

25 Like numerals refer to like parts throughout the several views of the drawings.

In the drawings, 5 represents a base which may be constructed either of wood or metal and which is preferably rectangular in form and has a flat under surface 6 and an undulated upper surface 7. An opening 8 extends entirely through the base 5 from top to bottom and is shaped similar to the outline of the sole of a shoe. Rigidly secured to the upper surface of the base 5 and extending entirely thereacross at the opposite ends thereof are angle bars 9 which are fastened to the base by bolts 10.

Located above the base 5 is a flexible casing 11 preferably consisting of an upper layer of leather 12 and an under layer of leather 13, both rectangular in form and stitched together adjacent to their edges at 14. The portions of the layers 12 and 13 inside the row of stitches 14 are separable. At its opposite ends the casing 11 is reinforced by narrow plates 15 which are located above the upper layer of leather and beneath the lower layer of leather and said plates are clamped to said casing by bolts 16. The casing 11 is sup-

ported at one end thereof, a short distance above the upper surface of the base 5, by means of the springs 17, one end of said springs being secured to an angle bar 9 and the other end of said springs being secured to the 55 casing. The other end of the casing is also secured above the base 5 by means of springs 18 which are in turn secured to screws 19 mounted in an angle bar 9 in which they may be adjusted by thumb nuts 20. The upper 60 and lower layers of leather comprising the casing 11 are stretched tightly lengthwise thereof by means of the springs 17 and 18 and the lengthwise tension upon the casing may be varied by manipulating the nuts 20. 65

Located within the container 11 between the flexible and separable upper and lower members 12 and 13 thereof is a flexible fluid container 21, preferably constructed of rubber and capable of holding either air or water 70 under pressure. The container 12 is supplied with a suitable valve 22 for admitting and discharging the pressure fluid which is preferably maintained at approximately 20 pounds pressure within the container. 75

In order to prevent a lateral movement of the casing 11 during the pressing operation side stays 23 consisting of flexible straps are secured to the opposite sides of the casing 11 and extend therefrom to a point beneath the base 5 where the opposite ends of said stays are secured together by means of springs 24. The side stays 23 are secured to the casing 11 by being inserted between the upper and lower layers 12 and 13 thereof and being secured thereto by the stitches 14. The ends of the stays 23, to which the springs 24 are secured, are reinforced by plates 25 which are clamped to the opposite faces of said stays by means of bolts 26. 80 85 90

As an aid in securing the instep portion of the sole to the instep portion of the shoe with the same effectiveness as the remainder of said sole, an instep support 27, preferably consisting of a block of rubber, is mounted beneath the instep pressing portion of the casing 11 upon a flat spring 28, one end of which is rigidly secured by means of bolts 29 to the under surface of the base 5 and the other end of said spring being loosely mount- 95 100

ed to slide upon a guide 30 which is in turn secured to the under surface of the base 5.

To eliminate possible friction between the under surface of the casing 11 and the upper surface of the base 5 during the pressing operation, rollers 31 are interposed between said surfaces, and said rollers may roll freely upon the upper surface of the base 5, the rotative movement of the rollers longitudinally of the base being limited by the engagement of the edge of head portions 32 of said rollers with the opposite sides of shallow grooves 33 which are provided in the opposite sides of the base 5. The head portions 32 also prevent the rollers from moving longitudinally thereof upon the base 5.

A shoe A to which a sole *a* is to be attached is mounted upon a last B in turn secured to a last holder C pivotally mounted at *c* to a support D, which in turn is secured to a plunger E. The position of the last holder C with respect to the support D is regulated by means of a plurality of adjusting screws *d*. The plunger E may be operated by any suitable hand or power driven mechanism.

The general operation of the device hereinbefore specifically described is as follows:— Assuming that it is desired to attach a sole *a* to a shoe upper A, the latter is placed upon the last B which at this time is located at a suitable distance above the casing 11. The upper surface of the sole *a* and under surface of the shoe A are first coated with suitable cement and the sole *a* is placed in position upon the shoe. The plunger E is then operated to lower the shoe A and sole *a* until the sole contacts with and compresses the casing 11 and preferably from 500 to 600 pounds pressure is provided between the shoe, sole and flexible casing. When this pressure is applied, the tendency of the casing 12 will be to compress and sag somewhat, stretching the springs 17 and 18 and forcing the lower layer of flexible material 13 of the casing 45 against the upper surface of the instep support 27 and the latter will be compressed somewhat and the spring 28 upon which it is mounted will sag slightly beneath the pressure. The action of the instep support 27 will be to compress the fluid container 21 at the instep portion of the latter against the instep pressing portion of the upper layer 12 of the casing 11 and the instep portion of the sole *a* will be forced against the instep portion of the shoe with the same pressure and effectiveness that is provided over the entire surface of the sole. During the pressing operation the side stays 23 and springs 24 will tend to hold the flexible casing 11 securely in position above the upper surface of the base 5 and beneath the shoe A. Each type of shoe may be positioned above the flexible casing 11 by positioning the last holder C relatively to the support D by means 85 of the adjusting screws *d*.

We claim:

1. A pressing device for a sole laying machine comprising, in combination, a base, a casing yieldingly supported upon said base and embodying therein separable layers of flexible material, an expandible and contractable fluid container located between said flexible layers, and means to prevent a lateral movement of the casing during the pressing operation.

2. A pressing device for a sole laying machine comprising, in combination, a base, a casing yieldingly supported upon said base and embodying therein separable layers of flexible material, an expandible and contractable fluid container located between said flexible layers, stays fast to said casing at opposite sides thereof, and yielding means fastened to opposite adjacent ends of said stays and securing the latter together beneath said base.

3. A pressing device for a sole laying machine comprising, in combination, a base, a casing yieldingly supported upon said base and embodying therein separable layers of flexible material, an expandible and contractable fluid container located between said flexible layers, a yielding member mounted upon said base beneath said casing, and a yielding instep supporting member mounted upon 95 said yielding member and located beneath an instep pressing portion of the casing.

4. A pressing device for a sole laying machine comprising, in combination, a base, a casing embodying therein upper and lower 100 separable layers of flexible material, springs supporting said flexible layers above said base, means to vary the tension on said springs, and an expandible and contractable fluid container located between said flexible 105 layers.

5. A pressing device for a sole laying machine comprising, in combination, a base, a casing yieldingly supported upon said base and embodying therein separable layers of 110 flexible material, an expandible and contractable fluid container located between said flexible layers, and anti-friction means interposed between the end portions of said casing and the upper surface of said base.

6. A pressing device for a sole laying machine comprising, in combination, a base, a casing yieldingly supported upon said base and embodying therein separable layers of flexible material, an expandible and contractable fluid container located between said flexible layers, a flat spring mounted upon said base beneath said casing, and a yielding instep supporting member mounted upon said spring and located beneath the instep pressing portion of the casing.

7. A pressing device for a sole laying machine comprising, in combination, a base, a casing embodying therein upper and lower 130 separable layers of flexible material, springs

supporting said flexible layers above said base, means to vary the tension on said springs, an expandible and contractable fluid container located between said flexible layers, stays fast to said casing at opposite ends thereof, and springs connected to the end portions of said stays.

8. A pressing device for a sole laying machine comprising, in combination, a base, a casing embodying therein upper and lower separable layers of flexible material, springs supporting said flexible layers above said base, means to vary the tension on said springs, an expandible and contractable fluid container located between said flexible layers, stays fast to said casing at opposite ends thereof, spring connected to the end portions of said stays and rollers interposed between the end portions of said casing and the upper 20 surface of said base.

9. A pressing device for a sole laying machine comprising, in combination, a base, a casing yieldingly supported upon said base and embodying therein separable layers of 25 flexible material, an expandible and contractable fluid container located between said flexible layers, means to vary the tension upon said casing, stays fast to said casing at opposite sides thereof, springs fastened to opposite adjacent ends of said stays and securing the latter together beneath said base, a yielding member mounted upon said base beneath said casing, and a yielding instep supporting member upon said yielding member and 35 located beneath the instep pressing portion of the casing.

In testimony whereof we have hereunto set our hands.

FRANK W. CHRISTY.
JAMES A. TORREY.
